UNITED STATES PATENT OFFICE

HORACE W. KING, OF ANN ARBOR, MICHIGAN, ASSIGNOR TO KING-SEELEY CORPORATION, OF ANN ARBOR, MICHIGAN, A CORPORATION OF MICHIGAN

LIQUID-DEPTH-INDICATING DEVICE

Application filed April 16, 1923. Serial No. 632,343.

The invention relates to depth indicating devices and is particularly applicable to motor vehicles for indicating the depth of fuel in the supply tank. One of the objects 5 of the invention is to provide a device which is dependent for its operation upon the partial return of the gasoline, which is being withdrawn from the supply tank, to the supply tank. Another object is the provision of 10 a device which can be readily attached to a supply tank having a drain opening. Further objects of the invention reside in the novel features of construction and combinations of parts as more fully hereinafter set forth.

15 In the drawings:

Figure 1 is a sectional elevation of a depth indicating device embodying my invention and applied to a liquid fuel supply tank;

Figure 2 is a perspective view partly broken away of the unit attached to the supply tank.

In the present instance 1 is the supply tank of a motor vehicle containing a liquid fuel such as gasoline and having in its bottom the 25 drain outlet opening 2 and in its top the fuel inlet opening 3 closed by the filler cap 4 provided with the air inlet opening 5. 6 is the vacuum tank of the motor vehicle located at a point above the supply tank 1.

30 My depth indicating device is constructed to be readily attached to the supply tank by removing the drain plug and inserting the unit comprising the air chamber and associated parts through the drain outlet opening 2 upwardly into the supply tank. This unit comprises the hexagonal body or nut 7 having the concentric vertically extending nipple 8 which is threaded into the wall of the drain outlet opening. The unit also comprises the tubular member 9 forming the air chamber and having a closed upper end and an open lower end, the air supply tube 10 and the air pressure tube 11 extending longitudinally within the tubular member 9. The lower end of the tubular member 9 is seated in the axially aligned recess 12 within the upper end of the nipple 8 and has the openings 13 in its wall above the bottom of the supply tank for placing its interior in communication with the gasoline in the supply tank. The

air supply tube 10 extends upwardly through an opening in the upper end of the tubular member 9, is sealed therein and also extends downwardly through the axial bore 14 in the nipple 8, the size of the air supply tube being such that sufficient clearance is provided in the bore 14 for the passage to the vacuum tank of the maximum amount of gasoline desired. Both the upper and lower ends of the air supply tube are open, the upper end terminating within the supply tank 1 above the surface of the gasoline therewithin while the lower end terminates within the transverse bore 15 in the hexagonal body or nut 7, this transverse bore communicating with the axial bore 14 in the nipple. 16 is a tube connected to a nipple 16' formed integral with the nut 7 for connecting the vacuum tank 6 with the transverse bore 15.

17 is a suitable pressure gage such as a U-shaped gage having one leg 18 open to the atmosphere and the other leg 19 connected to the tube 20 which has its lower end connected to the nipple 19' projecting from the hexagonal body or nut 7 and communicating with the transverse bore 21 in this body or nut which in turn communicates with the longitudinally extending bore 22 in the nipple 8. The lower end of the air pressure tube 11 is secured to the nipple 8 in communication with the bore 22 while its upper end is open and terminates near the upper closed end of the tubular member 9.

With the above construction the gasoline upon operation of the vacuum tank 6 is drawn from the supply tank 1 through the series of openings 13 in the tubular member 9, the axial bore 14 in the nipple 8, the transverse bore 15 in the hexagonal head or nut 7, and the tube 16 to the vacuum tank. The gasoline within the air tube 10 is also immediately withdrawn therefrom and then air is drawn downwardly through this air tube and commingles with the gasoline being withdrawn from the vacuum tank. In this connection the combined areas of the series of openings 13 is sufficient to avoid any liability of drawing the air within the tubular member 9 downwardly through the axial bore 14 and thence to the vacuum tank. Upon cessation

tion in operation of the vacuum tank which occurs when the proper amount of gasoline has been drawn thereinto the commingled gasoline and air in the tube 16 rushes back owing to the fact that the upper end of the tube 16 is above the supply tank 1. The gasoline returns into the body of the gasoline in the supply tank while the air rises into the tubular member 9 above its openings 13 to replace any air which has been lost. In the event that the supply of air is too great it will escape outwardly through the openings 13 into the body of the gasoline in the supply tank and rise upwardly therethrough. Since the pressure gage 17 is in communication with the upper end of the tubular member 9 which forms the air chamber, the pressure of the air within this air chamber is transferred to the pressure gage which can be suitably graduated to indicate either the depth or the quantity of gasoline in the supply tank.

From the above description it will be readily seen that I have provided a simple construction of device for measuring the depth or quantity of gasoline in a supply tank, this device including a unit which can be readily attached to the supply tank. It will also be seen that the operation of the device is dependent upon the return flow of the gasoline to the supply tank, the replenishing air being held in the gasoline being withdrawn and commingled therewith.

What I claim as my invention is:

1. The combination with a tank containing liquid and means for withdrawing liquid from said tank, of a member adapted to be secured in the bottom of said tank having a vertically extending liquid passage communicating with said withdrawing means; a tubular member secured to said first-mentioned member and extending upwardly within said tank, said tubular member having a closed upper end and an opening in its lower end communicating with said vertically extending passage and also a second opening communicating with the interior of said tank at the full depth of the liquid to be measured for placing the interior of said tubular member and said vertically extending passage in communication with the liquid in said tank, an air supply tube extending longitudinally within said vertically extending passage and having open upper and lower ends, the upper end thereof passing air tight through said tubular member and being above the normal level of liquid in said tank, and means for indicating the pressure of air in said tubular member.

2. The combination with a tank containing liquid and means for withdrawing liquid from said tank to a point higher than the surface of liquid in said tank, of a supporting member adapted to be secured in the bottom of said tank and having a vertically extending liquid passage communicating with

said liquid withdrawing means, a tubular member secured to said supporting member and extending upwardly within said tank, said tubular member having a closed upper end and an opening in its lower end registering with said vertically extending liquid passage, said tubular member also having a liquid inlet opening communicating with the interior of said tank at the full depth to be measured for placing said vertically extending passage in communication with the interior of said tank, an air supply tube extending longitudinally within said tubular member and vertically extending passage, said air supply tube extending air tight through the upper end of said tubular member and having open upper and lower ends, the upper end being above the normal surface of liquid in said tank and the lower end terminating within the lower portion of said supporting member, and means for indicating the pressure of air in said tubular member.

3. The combination with a tank containing liquid and means for withdrawing liquid from said tank to a point higher than the surface of liquid in said tank, a supporting member having an upwardly extending nipple adapted to be secured in the bottom of said tank, said supporting member and nipple being provided respectively with communicating liquid passages; a tubular member secured to said nipple and extending upwardly within said tank, said tubular member having a closed upper end, an open lower end registering with the liquid passage in said nipple and also a liquid inlet opening communicating with the interior of said tank at the full depth to be measured for placing the liquid passages in said supporting member and nipple in communication with the interior of said tank, an air supply tube extending longitudinally within said tubular member and passage in said nipple, said air supply tube extending air tight through the upper end of said tubular member and having open upper and lower ends terminating respectively above the normal surface of liquid in said tank and in the passage in said supporting member, a tube extending upwardly within said tubular member and having an open upper end, a pressure gage and connections therefrom communicating with the lower portion of said last-mentioned tube.

4. The combination with a liquid fuel supply tank and a vacuum tank for withdrawing the liquid fuel from said supply tank, of a supporting member having a head and a nipple, said nipple being adapted to be secured in the bottom of said tank and having a vertically extending liquid passage and said head having a transverse passage communicating with said vertically extending passage, means connecting said transverse passage with said vacuum tank, said nipple also having a second vertically extending passage, a tubular

member having an open lower end secured to said nipple and registering with said first-mentioned vertically extending passage therein, said tubular member extending upwardly within said tank and having a closed upper end and a liquid fuel inlet opening communicating with the interior of said tank at the full depth to be measured, an air supply tube extending within said tubular member and first-mentioned passage in said nipple, said air supply tube extending air tight through the upper end of said tubular member and having open upper and lower ends respectively terminating above the surface of liquid fuel in said tank and in the transverse passage in said head, a tube within said tubular member communicating with said second-mentioned vertically extending passage in said nipple and having an opening in its upper end, a pressure gage, and means connecting said gage with said second-mentioned vertically extending passage in said nipple.

5. The combination with a tank containing liquid and means for withdrawing liquid from said tank, of a member adapted to be secured to the bottom of said tank and having a passage, means connecting said passage with said withdrawing means, a hollow member carried by said first mentioned member and extending upwardly within said tank and having a closed upper end and an opening adjacent its lower end communicating with the interior of said tank at the full depth of the liquid to be measured for placing the interior of said hollow member and said passage in communication with the liquid in said tank, an air supply tube for introducing air into said passage, a pressure gage, and a pressure tube for placing said pressure gage in communication with the upper portion of the interior of said hollow member.

6. The combination with a tank containing liquid and means for withdrawing liquid from said tank, of a member adapted to be secured to the bottom of said tank and having a passage, means connecting said passage with said withdrawing means, a tubular member extending upwardly within said tank and having a closed upper end and an opening in its lower end communicating with said passage and also a second opening communicating with the interior of said tank at the full depth of the liquid to be measured for placing the interior of said tubular member and said passage in communication with the liquid in said tank, an air supply tube for introducing air into said passage, a tube extending upwardly within said tubular member and having an opening communicating with the interior of said tubular member near its upper end, a pressure gage and connections therefrom communicating with said last-mentioned tube.

7. The combination with a tank containing liquid, of a body adapted to be secured to the

bottom of said tank and having a passage for the liquid, a tubular member mounted upon said body and extending upwardly within said tank, said tubular member having an upper closed end and an opening in its lower end communicating with said passage and also a second opening communicating with the interior of said tank at the full depth to be measured, for placing said passage in communication with the interior of said tank, an air supply tube extending longitudinally of said tubular member and having an opening in its upper end located above the upper end of said tubular member and an opening in its lower end in communication with said passage, a pressure tube mounted upon said body and extending upwardly within said tubular member and having an opening in its upper end in communication with the interior of said tubular member near the upper end of the latter, a pressure gage and connections therefrom communicating with the lower end of said pressure tube.

8. The combination with a tank containing liquid, of an air chamber extending upwardly into said tank and having a closed upper end and communicating at its lower end with said tank, means connected to the bottom of said tank in communication with the lower end of said air chamber for withdrawing liquid from said tank, an upwardly extending pressure tube having its upper end in communication with the upper end of said air chamber and having its lower end below said tank, a pressure gauge and connection therefrom communicating with the lower end of said pressure tube, and means for introducing air into said air chamber including an upwardly extending air supply tube having its upper end opening into said tank above the normal level of the liquid, the lower end of said tube communicating with the lower portion of said air chamber.

9. The combination with a tank containing liquid, of a body adapted to be secured to the bottom of said tank and having a passage for the liquid, a tubular member mounted upon said body and extending upwardly within said tank, said tubular member having an upper closed end and an opening in its lower end communicating with said passage and also a second opening communicating with the interior of said tank at the full depth to be measured, for placing said passage in communication with the interior of said tank, an upwardly extending pressure tube mounted upon said body and having its upper end in communication with the upper portion of said tubular member, means for introducing air into said tubular member, a pressure gauge and connections therefrom communicating with the lower end of said pressure tube.

10. The combination with a tank containing liquid, of a body adapted to be secured to the

to the bottom of said tank and having a passage for the liquid, a tubular member mounted upon said body and extending upwardly within said tank, said tubular member having an upper closed end and an opening in its lower end communicating with said passage and also a second opening communicating with the interior of said tank at the full depth to be measured, for placing said passage in communication with the interior of said tank, means for introducing air into said tubular member, a pressure tube mounted upon said body and extending upwardly within said tubular member and having an opening in its upper end in communication with the interior of said tubular member near the upper end of the latter, a pressure gauge and connections therefrom communicating with the lower end of said pressure tube, said body, tubular member, and pressure tube being constructed to form a unit detachably secured to said tank.

11. The combination with a tank containing liquid, of an air chamber extending upwardly within said tank and having a closed upper end and communicating at its lower end with the liquid in said tank, means for withdrawing liquid from said tank, a connection for placing said liquid withdrawing means in communication with the lower portions of said tank and air chamber, a pressure tube opening into the upper portion of said air chamber, a pressure gauge, a connection between said pressure tube and gauge, and an upwardly extending air supply tube having an open upper end in communication with the air above the normal level of liquid within said tank and having its lower end opening into said first mentioned connection at a point below said air chamber.

In testimony whereof I affix my signature.
HORACE W. KING.
